US00D578882S

(12) **United States Design Patent**
Friedland et al.

(10) **Patent No.:** **US D578,882 S**
(45) **Date of Patent:** **** Oct. 21, 2008**

(54) **TRANSPARENT CONTAINER**

(75) Inventors: **Jason Michael Friedland**, Franklin, TN (US); **Matthew Wadalawala**, Manhattan Beach, CA (US); **John Heck**, Ostrander, OH (US); **Glenn Shull**, Los Angeles, CA (US); **Gary Chisholm**, Rancho Palos Verdes, CA (US); **Angus MacLellan**, Columbus, OH (US); **Neil A. Willcocks**, Brentwood, TN (US); **Alessandra Collier**, Franklin, TN (US)

(73) Assignee: **MARS, Incorporated**, McLean, VA (US)

(**) Term: **14 Years**

(21) Appl. No.: **29/287,909**

(22) Filed: **Oct. 1, 2007**

(51) LOC (8) Cl. **09-03**

(52) U.S. Cl. **D9/425; D7/545**

(58) **Field of Classification Search** D9/414, D9/418, 424-432; D7/354, 360, 505, 540-545, D7/554, 565-567, 570, 574, 584-586; D30/123, D30/129-133; 426/115, 122, 394; 206/216, 206/469, 497, 508, 557, 804, 815; 220/4.22, 220/266, 495.01, 574; 229/123.1, 125.35; D11/143

(57) **CLAIM**

The ornamental design for a transparent container, as shown and described.

DESCRIPTION

FIG. 1: is a perspective view of a first embodiment of a transparent container showing our new design;

FIG. 2: is a left side view of the design shown in FIG. 1;

FIG. 3: is a right side view of the design shown in FIG. 1;

FIG. 4: is a top view of the design shown in FIG. 1;

FIG. 5: is a front view of the design shown in FIG. 1;

FIG. 6: is a rear view of the design shown in FIG. 1;

FIG. 7: is a perspective view of a second embodiment of a transparent container showing our new design;

FIG. 8: is a left side view of the design shown in FIG. 7, the right side view being identical thereto;

FIG. 9: is a top view of the design shown in FIG. 7; and,

FIG. 10: is a front view of the design shown in FIG. 7, the rear view being identical thereto.

The bottom of the transparent container forms no part of the claimed design.

1 Claim, 4 Drawing Sheets
